BUTTON

Robert H. Wollin, Milwaukee, Wis.

Application February 27, 1943, Serial No. 477,350

3 Claims. (Cl. 24—90)

This invention relates to sewed-on buttons for use in the clothing industry on overcoats, sack coats, uniforms and the like.

The button to which my invention pertains has an integral neck portion through which the button is sewed on the garment and it is an object of my invention to provide said neck portion in elongated, tapered form to fit a correspondingly shaped buttonhole with the larger end of the neck portion at the larger end of the buttonhole and the smaller end of the neck portion towards the smaller end of the buttonhole to fit the neck portion within the buttonhole without undue pressure on or spreading of the same and having flat sides and rounded ends to avoid fraying or damaging the buttonhole in the movement of the neck portion therein.

A further object of my invention is to provide the neck portion with a substantially uniform cross-section throughout its height to avoid holding the garment layer having the buttonhole in a definite position on the neck portion whereby to prevent wrinkling or crowding of said garment layer at the button, especially with respect to the heavier overcoat materials where larger buttons are used.

A further object of my invention is to provide the neck portion of a length and width that the substantially flat surface in which the outer end of the neck portion terminates, although co-extensive with said cross-section, will have sufficient area to firmly support and maintain the button on the garment when sewed thereto in an outstanding position and to hold the button from sagging or hanging over in a tilted or tipped position to preserve a neat appearance for the garment whether buttoned or unbuttoned.

A further object of my invention is to provide the neck portion at its lower inner end with a rounded or curved corner so that the button, on being manipulated to unbutton it will not puncture the garment material in the repeated and frequent unfastening of the button in the use of the garment.

In accordance with my invention, the neck portion is perforated to provide openings to receive the sewing thread which secures the button to the garment layer, these openings being disposed in the respective button forms shown herein for a side sewing operation for one form and a straight through sewing for the other form as will hereinafter more fully appear.

In the accompanying drawing—

Fig. 1 is a top plan view of my improved button

in fastening relation with two overlapping layers of a garment;

Fig. 2 is a vertical sectional view with parts in elevation taken on line 2—2 of Fig. 1;

Fig. 3 is a bottom plan view of the button;

Fig. 4 is a cross-sectional view taken on line 4—4 of Fig. 2;

Fig. 5 is a bottom plan view of a button embodying the second form of my invention as above mentioned; and

Fig. 6 is a cross-sectional view taken on line 6—6 of Fig. 5.

In both forms of my invention as shown in the drawing, 1 indicates the neck portion of the button and 2 indicates the head portion thereof. These parts are integrally connected, it being intended to make the buttons in molded, one-piece form under pressure in a die of plastic materials of any desired colors. The head portion 2 may be given any shape desired, circular being shown herein, and in Figs. 1 to 4 the top surface 3 of the head portion 2 is crowned or domed shaped and which surface may be left blank or be ornamented, a suitable insignia being impressed thereon for buttons for use on military uniforms. In Figs. 5 and 6, the head portion 2 is circular, as before, but has a shallow dished top surface 4 to depress the upper loops of the sewing threads for the button below its top surface as in buttons of this design.

Regardless of the shape of the head portion 2 of either button, it is the essence of my invention to make the neck portion 1 of the button in elongated, tapered form to fit the correspondingly shaped buttonhole 5 with which the button is used as shown in Figs. 1 and 2. The larger end 6 of the neck portion is located at the larger end 7 of the buttonhole, while the smaller end 8 of the neck portion faces the smaller end 9 of the buttonhole. That is, the button is sewed on the garment layer 10 with the larger and smaller ends of the neck portion so arranged. This fits the neck portion 1 within the buttonhole 5 without undue pressure or spreading and fraying or damaging of the buttonhole in the relative movement of the parts is prevented.

The sides 11, 11 of the neck portion 1 are substantially flat, while the ends 6 and 8 of the neck portion at its opposite ends are rounded as shown herein. This provides smooth contacts for the neck portion with the edges of the buttonhole 5 or its binding thread 12 to avoid fraying or cutting of the same and frequent repairing of the buttonhole to keep the garment in good order is not required.

The neck portion 1 spaces the button head 2 sufficiently outward from the garment layer 13 to which the button is attached to receive the other garment layer 13 having the buttonhole 5 without crowding or binding as shown in Fig. 2. This is aided by having the neck portion 1 substantially uniform in cross-section throughout its height so that the side and end surfaces of the neck portion may continue uninterruptedly to the outer end of the neck portion for a smooth overlapment of the garment layers when fastened together by the button.

The neck portion 1 terminates at its outer end in a flat surface 14. This surface is co-extensive with the cross-section of the neck portion as shown herein. Said surface has an area sufficient to firmly support and maintain the button in outstanding relation on the garment layer 10 when sewed thereto. Hence the surface 14 holds the button from sagging or hanging over in a tilted position to preserve a neat appearance for the garment.

In both forms of button shown, the neck portion 1 has a rounded or curved corner 15 at its lower inner end to prevent puncturing the garment material in the manipulation of the button in unbuttoning it repeatedly and frequently in the use of the garment.

In Figs. 1 to 4, the neck portion 1 has a thread receiving opening 16 extending laterally through the neck portion so that the button may be sewed on the garment layer by a side sewing operation, the fastening thread 17 passing through the garment layer and the opening 16. The neck portion 1 has countersinking recesses 18, 18 in its sides at the opposite ends of the opening 16 to dispose the fastening thread 17 out of contact with the edges of the buttonhole to avoid cutting either of the same to fray the buttonhole or loosen the connection of the button with garment.

In the form of button shown in Figs. 5 and 6, the neck portion 1 has a pair of openings 19, 19 extending therethrough axially of the button to receive the fastening threads which sew the button on the garment layer. It will be noted from Fig. 6, that the openings 19 extend completely through the button from top to bottom, there being a bridge portion 20 therebetween to support the thread loops at the top end of the button. In a button of this type the fastening thread is completely housed within and protected by the neck portion 2. Both buttons are well adapted for use on overcoats and other garments comprised of the heavier materials, the neck portions firmly supporting the buttons in outstanding positions on the garments, saving the buttonholes and the fastening threads, and holding the buttons from tilting over and sagging to preserve the neat appearance required of the garment.

I claim as my invention:

1. A button adapted to be sewed on a garment layer comprising rigidly connected head and neck portions, said neck portion being in elongated, laterally tapered form to fit a correspondingly shaped buttonhole with the wider end of the taper at the larger end of the buttonhole and the narrower end of the taper towards the smaller end of the buttonhole to fit the neck portion within the buttonhole without undue spreading of the same, said neck portion having

substantially flat sides and rounded ends to avoid fraying the buttonhole by contact of the neck portion therewith, said neck portion being perforated to receive the sewing thread which secures the button on the garment layer, and said neck portion extending outwardly from the head portion to substantially a uniform extent throughout its length and terminating at its outer end in a substantially flat surface conforming to the tapered shape of the neck portion to firmly support the button throughout the length of the neck portion on the garment layer when sewed thereto and hold the button from sagging.

15 2. A button adapted to be sewed on a garment layer comprising rigidly connected head and neck portions, said neck portion being in elongated, laterally tapered form to fit a correspondingly shaped buttonhole with the wider end of the taper at the larger end of the buttonhole and the narrower end of the taper towards the smaller end of the buttonhole to fit the neck portion within the buttonhole without undue spreading of the same, said neck portion having substantially flat sides and rounded ends to avoid fraying of the buttonhole by contact of the neck portion therewith, said neck portion having an opening extending laterally therethrough to receive the sewing thread which secures the button to the garment layer and having countersinking recesses at the opposite ends of said opening to dispose the sewing thread out of contact with the sides of the buttonhole, said neck portion extending outwardly from the head portion to a substantially uniform extent throughout the length of the neck portion and terminating at its outer end in a substantially flat surface conforming to the tapered shape of the neck portion and co-extensive with the lateral dimension thereof to firmly seat the button through the length of the neck portion on the garment layer when sewed thereto and hold the button from sagging.

30 3. A button adapted to be sewed on a garment layer comprising rigidly connected head and neck portions, said neck portion being in elongated, laterally tapered form to fit a correspondingly shaped buttonhole with the wider end of the taper at the larger end of the buttonhole and the narrower end of the taper towards the smaller end of the buttonhole to fit the neck portion within the buttonhole without undue spreading of the same, said neck portion having substantially flat sides and rounded ends to avoid fraying the buttonhole by contact of the neck portion therewith, said neck portion having at least two openings extending therethrough axially of the button to receive the sewing thread which secures the button on the garment layer and dispose said thread within the neck portion and out of contact with the buttonhole, and said neck portion extending outwardly from the head portion to substantially a uniform extent throughout its length and terminating at its outer end in a substantially flat surface conforming to the tapered shape of the neck portion to firmly support the button throughout the length of the neck portion on the garment layer when sewed thereto and hold the button from sagging.

ROBERT H. WOLLIN.
